NICHOLAS HOPKINS, OF NEW YORK, N. Y.

Letters Patent No. 70,568, dated November 5, 1867.

IMPROVEMENT IN REGISTER-POINTS FOR PRINTING-PRESSES.

The Schedule referred to in these Letters Patent and making part of the same.

TO ALL WHOM IT MAY CONCERN:

Be it known that I, NICHOLAS HOPKINS, of the city, county, and State of New York, have invented a new and improved Point for Printing-Press; and I do hereby declare that the following is a full, clear, and exact description thereof, which will enable others skilled in the art to make and use the same, reference being had to the accompanying drawings, forming part of this specification, in which—

Figure 1 is a top view of my improved apparatus, open.

Figure 2 is a longitudinal section of the same, taken through the line x x , fig. 1.

Figure 3 is a top view of the same, showing a modified form of the bearers.

Similar letters of reference indicate corresponding parts.

My invention has for its object to furnish an improved device for the purpose of making holes in printed sheets preparatory to their being folded into book form by machinery, said point-holes being necessary to insure perfect register; and it consists in a hinged plate, having a metallic point attached to its movable part, to be used in connection with a piece of furniture; in the combination of one or more rubber or other elastic bearers with the movable part of the hinged plate; in the combination of a spring-catch with the piece of furniture and with the end of the movable part of the hinged plate, to hold it steady while being used; and in the combination of a spring with the piece of furniture and with the movable part of the hinged plate, to throw it closed automatically when released from the spring-catch; the whole being constructed and arranged as hereinafter more fully described.

A represents a portion of a piece of furniture, which may be five-em, three-em, or any other desired size. B is a metallic plate, hinged at its middle point, the part b^1 of which is secured to the piece of furniture in such a way that when the two parts b^1 and b^2 are shut up or folded together, the upper surface may be flush with the surface of the piece of furniture. To the middle of the movable part b^2 is attached a metallic point, C, as shown in figs. 1, 2, and 3. The point C may be removably attached to the plate B by having a screw-thread cut upon its lower end screwing into the said plate. D are bearers, attached to the part b^2 of the hinged plate B, upon each side of the point C, to prevent the rollers from being injured by the said point. The bearers D should be elastic, so as to give to allow the point to perforate the sheet. This elasticity may be obtained by making them of India rubber, or by placing springs beneath them, or in any other convenient way. If desired, the bearers D may be replaced by a cone-shaped bearer through a hole, through the centre of which the point C passes, as shown in red in fig. 3. E is a catch, pivoted in a recess at the end of the plate B, so as to take hold of the free end of the part b^2 and hold it steady while the point is being used. The catch E is held forward by a spring, F, attached to its lower end, as shown in fig. 2. G is a spring, placed in a recess beneath the movable part b^2 , to throw it shut automatically when released from the catch E.

In using the device, as many points should be used as holes will be required, and they are placed at such a distance apart in making up the form as may be required to correspond with the points of the folding machine. The form is now locked up, securing the points firmly in place, and the movable parts b^2 are opened and secured by the spring-catch E. The sheet is then printed upon one side, the points C forming the necessary holes in the sheet. In printing the first side of the sheet the tympan-sheet remains stationary, but in printing the second side it moves slightly after each impression, so that if the points C were left exposed they would in a short time cut slits in it and destroy it. To guard against this, when the second side is being printed the part b^2 is shut down upon the part b^1 , the point C and bearers D passing into recesses in the furniture, as shown in figs. 1 and 2.

Having thus described my invention, what I claim as new, and desire to secure by Letters Patent, is—

1. The hinged plate B, having a metallic point, C, attached to its movable part to be used in connection with a piece of furniture in making up the form, substantially as herein shown and described, and for the purpose set forth.

2. The combination of one or more rubber or other elastic bearers D with the movable part b^2 of the hinged plate B, substantially as herein shown and described for the purpose set forth.

The above specification of my invention signed by me this 2d day of April, 1867.

NICHOLAS HOPKINS.
